Primary Examiner — Sheryl Lane*Assistant Examiner* — Nicole C Shiflet(74) *Attorney, Agent, or Firm* — Middleton Reutlinger(57) **CLAIM**

The ornamental design for a stove grate, as shown and described.

DESCRIPTION

FIG. 1 is an upper perspective view of a stove grate; FIG. 2 a top view of the stove grate of FIG. 1; FIG. 3 is a bottom view of the stove grate of FIG. 1; FIG. 4 is a front view of the stove grate of FIG. 1; FIG. 5 is a rear view of the stove grate of FIG. 1; FIG. 6 is a first side view of the stove grate of FIG. 1; and, FIG. 7 is a second side view of the stove grate of FIG. 1. The broken lines shown in the drawings are included for the purpose of illustrating unclaimed portions of the stove grate. The broken lines form no part of the claimed design.
